BLADE HOLDER

Duryea Bensel, New York, N. Y., assignor to
Hugo Mock, New York, N. Y.

Application April 27, 1934, Serial No. 722,647

5 Claims. (Cl. 206—16)

This invention relates to improvements in blade holders and more especially to the blade holders for holding used razor blades of the wafer or Gillette type.

The principal object of the invention is the provision of a convenient holder for wafer razor blades in which the blade will be safely held when not used, in which the blade may be conveniently and quickly extruded for use, and in which the blade is replaceable at will.

Further objects of the invention will be apparent from the specification and drawing in which:—

Fig. 1 is a perspective view of the holder with the blade concealed therein.

Fig. 2 is a perspective view of the holder with the blade extruded and in operative condition.

Fig. 3 is a sectional view along the line 3—3 of Fig. 1.

Fig. 4 is a perspective view of the interior holder for the blade into which the blade is directly inserted.

Fig. 5 is a perspective view of the exterior holder into which the holder shown in Fig. 4 fits.

Fig. 6 is a top view of the blank from which the holder shown in Fig. 5 is formed.

Fig. 7 is a top plan view of the blank from which the holder shown in Fig. 4 is formed.

10 designates the outside holder having a slot 11 cut therein; 12 and 13 designate the opposite sides of the outer holder 10; 14 designates the inner holder shown in blank form in Fig. 7; 15 is the finger-piece extending through the slot 11 and which may be formed integrally from the surface of the blank shown in Fig. 7; 16 is a slight protuberance formed in the holder 14 which acts to retard frictionally the movement of the holder 14 within the outer holder 10; 18 and 19 represent the opposite sides of the holder 14; 17 is the blade.

The blank 14 is made from sheet brass or other flexible metal and integral therewith is formed a thumb-piece 15 which is adapted to slide in the slot 11. Also integral therewith is the slight protuberance 16 which is intended to retard the movement of the holder 14 in and out of the holder 10.

The holder 10 is formed from a sheet of brass or other flexible metal but of heavier gauge than the metal forming the inner holder 14.

To insert the holder 14 within the holder 10 after both 10 and 14 are in the forms shown respectively in Figs. 4 and 5, the lower edges of

the holder 10 are lifted so as to provide space for insertion of the finger-piece 15, and the holder 14 is then sprung into place.

The blade 17 may be inserted into the holder 14 either before or after the holder is in position.

The holder 14 should be made of metal sufficiently springy so as to retain a firm grip upon the blade 17, but considerably thinner than the stock of which the holder 10 is made.

It should also be noted that the blank of the holder 14 is not bent at the center but at a distance from the center as the side 19 is somewhat longer than the side 18, to permit the easier insertion of the blade.

Having fully described my invention what I claim is:—

1. A blade holder for wafer razor blades comprising a folded cover member, a folded blade carrier held inside of the cover member, slots 20 within said cover member and within said blade carrier registering with each other, and means to reciprocate said blade carrier within said cover member.

2. A blade holder for wafer razor blades comprising a folded cover member having a slot, a folded blade carrier having a slot held within the cover member and a pintle attached to the blade carrier by which the blade may be retracted in and out of the cover member.

3. A blade holder for wafer razor blades comprising an outer member of two equal sized leaves joined together, a blade carrier held within said leaves, a slot in one of said leaves and in said blade carrier registering with each other, 35 and a thumb-piece attached to said carrier by which said blade may be reciprocated within said slot.

4. A blade holder comprising a folded cover member, a slot in said cover member, a flexible 40 blade carrier attached to and inserted within said cover member, and a thumb-piece attached to the blade carrier by which the razor blade may be reciprocated within said cover member.

5. A blade holder comprising a cover member, 45 a slot in said cover member, a flexible and resilient blade carrier having a slot therein and holding the blade, and a thumb-piece attached to the blade carrier by which the blade may be reciprocated in and out of said cover member.

DURYEA BENSEL.
